Patented Mar. 6, 1923.

UNITED STATES PATENT OFFICE.

CHARLES FREMONT GOLDEN, OF DENVER, INDIANA.

DRAFTING INSTRUMENT.

Application filed July 20, 1922 Serial No. 576,334.

To all whom it may concern:

Be it known that I, CHARLES FREMONT GOLDEN, a citizen of the United States, residing at Denver, in the county of Miami and State of Indiana, have invented a new and useful Drafting Instrument, of which the following is a specification.

The device forming the subject matter of this application is a drafting instrument, and the invention aims to provide suction means for holding the instrument on a blackboard, the suction means being housed, and the housing for the suction means constituting an important reinforcement for the instrument, the suction means being so located that it will form a useful guide for placing the instrument at the right place, approximately on the blackboard.

It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

In the accompanying drawings:—

Figure 1 shows in top plan, a drafting instrument constructed in accordance with the invention; Figure 2 is a bottom plan; Figure 3 is a longitudinal section; Figure 4 is a cross section on the line 4—4 of Figure 2.

The device forming the subject matter of this application includes a protractor head 1 comprising a straight base 2 and a curved limb 3, an arm 4, of any desired length, projecting from the base 2. A cross piece 5 extends between the base 2 and the limb 3 and constitutes, in effect a continuation of the arm 4. The fiducial edge 6 of the arm 4 is alined with the fiducial edge 7 of the cross piece 5, and the fiducial edges 6 and 7 are disposed at right angles to the fiducial edge 8 of the base 2. The limb 3 is inscribed with degree scales 9 reading in opposite directions from a zero point 10 alined with the fiducial edges 7 and 6 of the parts 5 and 4. The base 2 is provided

with scales 11 which read in opposite directions from a zero point alined with the fiducial edges 6 and 7 of the members 4 and 5. The arm 4 has a scale 12 reading from a zero point alined with the fiducial edge 8 of the base 2, the arm 4 having openings 14 coinciding with the unit graduations of the scale 12, and of sufficient size, preferably to receive a piece of chalk.

The arm 4 is connected with the base 2 by an integrally formed, hollow cup-shaped hub 15. This hub 15 is an important feature of the device. It forms a strong connection between the base 2 and the arm 4. A reinforcement at this point is important, because the tool, preferably is made in relatively large size for blackboard use, and, at the same time, must be made light. Since the tool is intended primarily for use on a blackboard in a school and is not handled ordinarily by an engineer, draftsman, or other person likely to exercise extreme care, the device is subjected to hard use, and there is a very good reason for reinforcing it, by means of the hub 15. The hub 15 terminates in a reduced neck 16 wherein a plunger 17 is mounted for right line reciprocation, the plunger being supplied at its outer end with a button 18. A compression spring 19 surrounds the plunger 17, one end of the spring engaging the button 18, and the other end of the spring engaging the neck 16. On the inner end of the plunger 17, there is a securing element 20, such as a headed screw, retaining a resilient cup-shaped suction member 21, preferably made of rubber, the size of the suction member being such that when it is retracted into the hub 15 by the action of the spring 19, the suction member will be housed within the hub. When the suction member is retracted, as aforesaid, the reduced tip 29 on the suction member engages the inner surface of the hub 15 and spaces the suction member from the inner surface of the hub. The suction member, therefore, does not tend to stick in the hub, but may be advanced, readily out of the hub, when pressure is applied to the button 18 of the plunger 17. The center 22 of the suction member 21 and the center of the button 18 coincide with the fiducial edges 6 and 8 of the members 4 and 2 and are located at the apex of the angle defined by the said edges. Consequently, the button 18 furnishes an

important index whereby the suction member 21 may be placed, approximately, at the desired point on the blackboard.

The base 2 is provided on its under side 5 with a groove 23 and there is a like groove 24 in the under surface of the limb 2. Where the grooves 23 and 24 communicate, at the corners of the head 1, pads 25, made of felt or the like are seated and held. 10 These particular parts 25 are subjected to more wear than are any of the parts hereinafter alluded to, and since the parts 25 are seated in the communicating portions of the grooves 23 and 24, the parts will be held 15 securely in place. The cross piece 5 may be extended across the groove 24 in the limb 3, as shown at 26, this portion of the cross piece carrying a pad 27. Pads 28 may be distributed along the arm 4. It will be understood, however, that all of the parts may 20 be located as desired. The function of the parts is to prevent the tool from scratching the blackboard.

In practical operation, the plunger 17 is thrust inwardly by means of the button 18, the spring 19 being compressed, and the suction member 21 acquiring a hold on the blackboard. The tool, therefore, is mounted on the blackboard for swinging movement 25 and if a piece of chalk be placed in one of the openings 4, the circle or the arc of a circle may be struck. By making a mark on the blackboard, coincident with the zero point 10 to serve as an index, the fiducial edge 6 of the arm 4 may be used to draw 30 a radial line with respect to the center 22, the instrument, therefore, being capable of use as a protractor. The fiducial edges 6 and

8 may be employed to draw lines at right angles to each other. Should it be desired 40 to extend, beyond the center 22, a line drawn along the fiducial edge 6 of the arm 4, the fiducial edge 7 of the cross piece 5 comes into play.

What is claimed is:—

1. A tool of the class described, including a protractor head comprising a curved limb and a base, and an arm projecting from the base, the base and the arm having fiducial edges defining a right angle, a cup-shaped hub joining the arm to the base and reinforcing them at their point of juncture, and a compressible suction member slidable in the hub and housed in the hub when retracted. 45

2. A device of the class described, constructed as set forth in claim 1 and further characterized by the fact that the center of the suction member is located at the apex of said angle. 50

3. A tool of the class described, constructed as set forth in claim 1, and further characterized by the provision of spring means for retracting the suction member, the suction member including a reduced tip, 65 which, cooperating with the hub, spaces the suction member from the hub when the suction member is retracted.

In testimony that I claim the foregoing as my own, I have hereto affixed my signature in the presence of two witnesses. 70

CHARLES FREMONT GOLDEN.
